(57) **CLAIM**

The ornamental design for a universal SDS-page loader, as shown and described.

DESCRIPTION

FIG. 1 is a front view of a universal SDS-page loader showing the new design;

FIG. 2 is a right side view thereof;

FIG. 3 is a bottom view thereof.

FIG. 4 is a top right front isometric view thereof;

FIG. 5 is a top left rear isometric view thereof;

FIG. 6 is a rear view thereof;

FIG. 7 is a left side view thereof; and,

FIG. 8 is a top view thereof.

The broken line showing of the universal SDS-page loader is for the purpose of illustrating portions of the article and forms no part of the claimed design.
